UNITED STATES PATENT OFFICE.

WALLACE L. BROOKS, OF SCHENECTADY, NEW YORK, ASSIGNOR TO GENERAL ELECTRIC COMPANY, A CORPORATION OF NEW YORK.

ELECTRIC-CURRENT SHUNT.

1,100,708.

Specification of Letters Patent. Patented June 23, 1914.

Application filed November 4, 1912. Serial No. 729,542.

To all whom it may concern:

Be it known that I, WALLACE L. BROOKS, a citizen of the United States, residing at Schenectady, county of Schenectady, State of New York, have invented certain new and useful Improvements in Electric-Current Shunts, of which the following is a specification.

My invention relates to electric current shunts, and particularly to shunts for use in alternating current circuits carrying large currents.

The object of my invention is to provide a shunt having negligible inductance.

The novel features which I believe to be characteristic of my improved shunt will be definitely indicated in the claims appended hereto. The principle of operation and details of construction will be understood by reference to the following description taken in connection with the accompanying drawings which illustrate my invention and show an embodiment thereof, and in which:—

Figure 1 illustrates diagrammatically the present construction of a well known type of shunt; Fig. 2 illustrates diagrammatically the construction of my improved non-inductive shunt of the same type; Fig. 3 is an enlarged perspective view of a practical embodiment of my invention; Fig. 4 is an end elevation of a commercial form of shunt embodying the features of my invention; Fig. 5 is a side elevation of the shunt shown in Fig. 4; and Fig. 6 is an enlarged section on the line 6—6 of Fig. 4.

My invention will be most readily understood and appreciated by considering a typical form of electric current shunt employed at the present time and diagrammatically illustrated in Fig. 1 of the drawings. This shunt comprises a pair of terminals A and B, between which are connected the conducting members C. These members generally consist of strips of sheet resistance metal. The width and number of these strips depend upon the desired capacity of the shunt. The ends of the strips are connected to the opposite terminals A and B, as indicated in Fig. 1; so that the ends of the strips connected to one terminal are adjacent to one another, and similarly the ends

of the strips connected to the other terminal are adjacent to each other. By such a construction it is evident that the current flows in a majority of the adjacent current conductors in the same direction. The inductive effect of the two middle conductors can be made to neutralize each other, but the inductive effect of the outer conductors will not have such an effect and the shunt as a whole will accordingly have more or less inductance.

My invention consists in arranging the conducting members in such a manner that the direction of the current flowing in any section of any conducting member is opposite to that of the current flowing in any adjacent section of a conducting member. Such an arrangement of the conducting members is indicated diagrammatically in Fig. 2, where A and B represent the terminals and C' the conducting members. It will be seen from this figure that the ends of the conducting members are alternately connected to the respective terminals. By such an arrangement the current in any two adjacent current conductors is opposite in direction, and the inductive effect of the current in one conductor will be neutralized by that of the current in an adjacent conductor if the conductors are placed near enough together. The nearer the adjacent conductors are brought together, the greater will be the neutralizing effect of one conductor upon the adjacent conductors. The novel arrangement which I have provided permits the conductors to be brought almost into contact with one another and results in a shunt having negligible inductance.

In Fig. 3 of the drawings, I have shown on an enlarged scale a practical embodiment of my invention. The terminal blocks 10 and 11 are of peculiar and novel construction. Each terminal block is provided with a series of alternately positioned contact studs 12 and recesses 13. The contact studs may be integral with the terminal blocks or may be secured thereto in any suitable manner. Contact studs 12 of one terminal block are opposite the recesses 13 of the other terminal block and accordingly the recesses of the former terminal block

are opposite the contact studs of the latter terminal block. Thus the contact studs of one terminal block are staggered with respect to the contact studs of the other terminal block. The current conducting members 14 are U-shaped and have a portion of one end attached to the contact stud of one terminal block and the other portion of the same end extending into the opposite recess 10 of the other terminal block. The other end of the conducting member has a portion similarly attached and a portion similarly extending into the adjacent contact stud and recess, respectively.

15 I have employed throughout the specification and claims of this application the term "conducting member" to designate means for conducting the current from one terminal block to the other terminal block, while 20 I have used "conductor" to designate individually those portions of a conducting member carrying current in substantially opposite directions.

The preferred embodiment of my invention is shown in Figs. 4, 5 and 6. The terminal blocks 10 and 11 of these figures are constructed the same as shown in Fig. 3. A reference to Fig. 6 will give a better understanding of the construction of these terminal blocks and the relation of the conductors thereto. It will be seen from this 25 figure that the contact studs 12 of each terminal block are alternately positioned with reference to the recesses 13 of the same block and that the contact studs of one block are opposite the recesses of the other block. Contact studs 12 have an L-shaped offset of the same thickness as that of the conductors, so that the surface of the conductor is continuous with that of the contact stud. This 30 offset serves for the reception of one portion of the end of the attached conductor. Insulating material 15 is forced into or assembled in the spaces between the conductors and the terminal blocks and also in the space between the terminal blocks themselves.

The conducting members shown in the 35 construction of Figs. 4, 5 and 6 each consists of a pair of conductors 16 of strips of sheet metal, such as manganin. The outer ends of these pairs of conductors are electrically connected by small pieces of metal 17 secured thereto. The spaces between the conductors of the same conducting member and between the conducting members themselves are filled with a thin layer or film of insulating material 21. I prefer to employ 40 sheets of pure mica of about .005 inch thickness for the insulating material 21, but it is obvious that other insulating agents, such, for example, as lacquer, may be used if desired.

The adjacent conductors in which the cur-

rent is flowing in opposite directions should 45 be as near together as possible. The nearer together such conductors are positioned, the more nearly will the inductive effect of the one conductor be neutralized by that of the other. The construction which I have 50 shown in Figs. 4, 5 and 6 permits the conductors to be placed so near together that they may be regarded as substantially in contact. The thickness of the insulating material 21 between the adjacent conductors 55 may be extremely small, for example, .005 or less of an inch, since the voltage between the adjacent conductors is very low. Such a shunt is adapted to carry a very heavy current, for example, one thousand or more 60 amperes, without appreciable inductive effect.

Each terminal block is provided with a contact screw or screws 18 for attaching a leading-in wire. For convenience in adjusting the resistance of the conducting members to the proper value, a lug 19 may be fastened to or cast on each terminal block and a thin strip of resistance material 20 may be connected between these lugs. 70 This strip of resistance material is convenient of access and can be filed or drilled to obtain final adjustment of the resistance of the shunt.

While I have herein shown and particularly described a preferred embodiment of my invention, it is obvious that changes may readily be made without departing from the spirit thereof, and I do not wish, therefore, to be limited to the precise disclosures herein set forth.

What I claim as new and desire to secure by Letters Patent of the United States, is:—

1. An electric current shunt, comprising a pair of terminals, a plurality of current conductors, and means for connecting the current conductors to the terminals so that the direction of the current in any current conductor is opposite to that of the current in any adjacent current conductor.

2. An electric current shunt, comprising a pair of terminals, a plurality of conducting members, each conducting member comprising two current conductors, and means for connecting said conducting members to the terminals so that the direction of the current flowing in any conductor is opposite to that of the current flowing in any adjacent conductor.

3. An electric current shunt, comprising a pair of terminals, a plurality of U-shaped conducting members connected between said terminals, said conducting members being arranged side by side and so connected to the terminals that the direction of the current in any two adjacent current conductors is opposite.

4. An electric current shunt, comprising a

pair of terminal blocks, each terminal block having a plurality of contact studs, the contact studs of one terminal block being staggered with respect to the contact studs of the other terminal block, and a plurality of conducting members, each conducting member having one end secured to a contact stud of one terminal block and the other end secured to an adjacent contact stud of the other terminal block.

5. An electric current shunt, comprising a pair of terminal blocks, each terminal block having a plurality of contact studs, the contact studs of one terminal block being staggered with respect to the contact studs of the other terminal block, and a plurality of U-shaped conducting members, each member having one end electrically connected to a contact stud of one terminal block and insulated from the other terminal block and the other end connected to an adjacent stud of the latter terminal block and insulated from the former terminal block.

6. A terminal block for an electric current shunt having a plurality of contact studs with an intervening space between adjacent studs, each contact stud having a recessed portion, and a current conductor having one end seated in the recessed portion of each stud and secured to the stud, the space between adjacent studs being wide enough to accommodate one end of a current conductor without electrical contact with either adjacent stud.

5. 7. An electric current shunt, comprising a pair of terminals, a plurality of conducting members separated from each other by a thin layer of insulating material, and means for connecting the conducting members to the terminals so that the direction of the current in any section of any conducting member is opposite to that of the current in any adjacent section of a conducting member.

8. An electric current shunt, comprising a pair of terminals, a plurality of conducting members, each conducting member comprising two current conductors, and means for connecting said conducting members to the terminals, said current conductors being arranged near to but insulated from each other and so that the direction of the current flowing in any conductor is opposite to that of the current flowing in any adjacent conductor.

55. 9. An electric current shunt, comprising a pair of terminals, a plurality of U-shaped conducting members connected between said terminals, said conducting members being arranged side by side and near to but insulated from each other and so connected to the terminals that the direction of the current in any two adjacent conductors is opposite.

10. An electric current shunt, comprising

a pair of terminal blocks, each terminal block having a plurality of contact studs, the contact studs of one terminal block being staggered with respect to the contact studs of the other terminal block, a current conductor connected to each contact stud, said current conductors being arranged side by side and separated from each other by a thin layer of insulating material, and means for electrically connecting said conductors in pairs so that the current in any two adjacent conductors is opposite in direction.

11. An electric current shunt, comprising a pair of terminal blocks, each terminal block having alternately arranged contact studs and recesses, the recesses and contact studs of one terminal block being opposite the contact studs and recesses respectively of the other terminal block, a plurality of U-shaped conducting members, each conducting member having a portion of one end secured to the contact stud of one terminal block and the other portion of the same end insulatively secured in the opposite recess of the other terminal block and having a portion of the other end insulatively secured in a recess adjacent to said above mentioned contact stud of the former terminal block and the other portion of the last mentioned end secured to a contact stud adjacent to said above mentioned recess of the latter terminal block.

12. An electric current shunt, comprising a pair of terminal blocks, each terminal block having alternately arranged contact studs and recesses, the contact studs and recesses of one terminal block being opposite the recesses and contact studs respectively of the other terminal block, a plurality of current conductors, each conductor having a portion of one end secured to a contact stud on one terminal block and the other portion of the same end extending into the opposite recess of the other terminal block, means at the opposite end of the conductors for electrically connecting them in pairs so that the current in any two adjacent conductors is opposite in direction, and means for insulating the portion of a conductor extending into a recess of a terminal block from such terminal block.

13. An electric current shunt, comprising a pair of terminal blocks, each terminal block having alternately arranged contact studs and recesses, the contact studs and recesses of one terminal block being opposite the recesses and contact studs respectively of the other terminal block, a plurality of current conductors arranged side by side and near to but insulated from each other, each conductor having a portion of one end secured to a contact stud on one terminal block and the other portion of the same end extending into the opposite recess of the other

1,100,708

terminal block, means at the opposite end of the conductors for electrically connecting them in pairs so that the current in any two adjacent conductors is opposite in direction, and means for insulating the portion of a conductor extending into a recess of a terminal block from such terminal block.

In witness whereof, I have hereunto set my hand this 31st day of October, 1912.

WALLACE L. BROOKS.
